ADJUSTABLE WRENCH

Filed Jan. 31, 1929

FIG. 1

FIG. 2

FIG. 3

HAROLD NELSON
INVENTOR

PER *Gut Helm*
ATTORNEY

UNITED STATES PATENT OFFICE

HAROLD NELSON, OF NEW WINDSOR, ILLINOIS

ADJUSTABLE WRENCH

Application filed January 31, 1929. Serial No. 336,573.

This invention relates to improvements in adjustable wrenches, and has for one of its principal objects the provision of a wrench adapted to readily grip and turn objects to be worked upon, such as nuts, bolts, pieces of pipe, and the like.

One of the principal objects of this invention is to provide a wrench suitable for use with pipes which will automatically grip the pipe and retain a firm hold upon the cylindrical surface of the same.

Another and further important object of this invention is the provision of a quick release means whereby after the turning action upon the pipe has been accomplished, the grip of the wrench will be immediately and automatically released so as to enable either the ready withdrawal of the wrench or another grip for additional turning movement.

Still another and further important object of this invention is to provide a wrench for pipes or the like which will be readily adjustable to practically any size of pipe while at the same time embodying the quick gripping and automatic release features heretofore described.

Other and further important objects of the invention will be apparent from the disclosures in the accompanying drawings and following specification.

The invention, in a preferred form, is illustrated in the drawings and hereinafter more fully described.

In the drawings:

Figure 1 is a side elevation of the improved adjustable wrench of this invention.

Figure 2 is a similar view, partly in section, illustrating the details of construction.

Figure 3 is a top plan view of the wrench.

As shown in the drawings:

The reference numeral 10 indicates generally the handle of the wrench, preferably provided with a longitudinal slot 12 which provides for lightness without reducing the strength of the handle and at the same time affords a ready means for hanging the wrench upon a hook or the like for safe keeping.

Integral with the end of the handle 10 is a jaw member 14 having gripping teeth 16 cut in the face of the same, these teeth being in

the form of downwardly inclined notches as illustrated.

The jaw member 14 is formed with two openings therein, one transverse and one longitudinal, the longitudinal opening serving to receive the threaded shank 18 of a corresponding jaw member 20, the face of which is provided with notches or gripping elements 22, these being cut upwardly, as shown in the drawings, to form a reverse gripping surface as compared with the notches 16. In the transverse opening of the jaw 14 is positioned a knurled adjusting nut 24 which is interiorly screw-threaded and fitted upon the shank 18. Obviously, a rotation of the knurled nut 24 will cause an adjustment of the distance between the gripping faces 16 and 22 of the jaws 14 and 20 respectively.

The shank 18 has a longitudinal slot 26 formed therein and in this slot is fitted a pin 28 or the like which slides readily in the same and the ends of which are mounted in the links 30 which extend upwardly adjacent the shoulder formed in the rear of the jaw element 14, and moved in countersunk grooves 32 provided therefor in the handle 10 adjacent the said shoulder.

Pivottally attached to the upper ends of the links 30 by means of pins or rivets 34 are the ends of a bifurcated lever 36 which is pivotally mounted at 38 by means of a bolt or the like passing through the handle 10.

A leaf spring 40 is positioned upon the upper face of the handle in such a manner as to normally force the lever 36 outwardly from the handle, the end of the leaf spring 40 being curved as shown at 42, and operating in a slot 44 formed in the underface of the lever 36.

Another leaf spring 46 is positioned directly underneath the handle, having its free end adjacent and contacting with the shank 18 of the movable jaw 20. The action of this leaf spring is co-operative with that of the spring 40 in forcing the rear end of the shank 18 downwardly when pressure on the lever 36 is released, thereby serving to immediately eliminate the gripping action of the jaws 14 and 20 upon the object to which they have been applied.

It will be noted that the shank 18 passes through a rather closely fitting opening in the jaw 14 so as to provide a pivotal action over the points 46 and 48 as best illustrated 5 in Figure 2.

It will be apparent that herein is provided an adjustable wrench which is practically automatic in its operation both as to gripping and release action as a pull on the lever

10 36 will immediately act to draw the shank 18 closer to the handle 10 of the wrench, thereby forcing the jaws 14 and 20 together with a combined leverage whereby an enormous gripping force is immediately available.

15 Again, the gripping force is immediately released as soon as any turning effort upon the wrench handle ceases.

I am aware that many changes may be made, and numerous details of construction 20 varied throughout a wide range without departing from the spirit of this invention, and I therefore do not purpose limiting the patent granted hereon otherwise than as necessitated by the prior art.

25 I claim as my invention:

An adjustable wrench, including a handle, a pair of jaws, one jaw relatively movable, and the other integral with the handle, means for adjusting the distance between the jaws, 30 said means comprising a screw-threaded shank on the movable jaw passing through an opening in the fixed jaw, said opening being at right angles to the operating face of the jaw and behind the same, an adjusting nut 35 on the screw-threaded shank, said adjusting nut operating in an opening in the fixed jaw, said opening being substantially parallel to the operating face of the jaw, a link, a cross pin in the link, said cross pin operating in a 40 slot in the screw-threaded shaft, a lever mounted on the wrench handle and substantially parallel thereto, one end of the lever being pivotally connected to the aforesaid link, said lever and link constituting means 45 for turning said movable jaw with the nut fulcruming in said opening.

In testimony whereof I affix my signature.
HAROLD NELSON.
